(57) **CLAIM**

The ornamental design for a mobile photo device, as shown and described.

DESCRIPTION

FIG. 1 is a front right perspective view of the mobile photo device showing my new design;

FIG. 2 is a front right perspective view thereof with bounce card open;

FIG. 3 is a front elevational view thereof;

FIG. 4 is a front elevational view thereof with bounce card open;

FIG. 5 is a rear elevational view thereof;

FIG. 6 is a rear elevational view thereof with bounce card open;

FIG. 7 is a top plan view thereof;

FIG. 8 is a top plan view thereof with bounce card open;

FIG. 9 is a side elevational view thereof;

FIG. 10 is a side elevational view thereof with bounce card open;

FIG. 11 is a rear right lower perspective view thereof; and,
FIG. 12 is a rear left perspective view thereof with bounce card open.

The broken lines in the drawings illustrate portions of the mobile photo device and form no part of the claimed design.

1 Claim, 12 Drawing Sheets
